(57) **CLAIM**

The ornamental design for the polishing or grinding pad assembly with abrasive disk, spacer, reinforcement and pad, as shown and described.

DESCRIPTION

FIG. 1 is a bottom perspective view of a polishing or grinding pad assembly with abrasive disk, spacer, reinforcement and pad of the present invention;

FIG. 2 is a bottom plan view of the polishing or grinding pad assembly with abrasive disk, spacer, reinforcement and pad of FIG. 1;

FIG. 3 is a side elevational view of the polishing or grinding pad assembly with abrasive disk, spacer, reinforcement and pad of FIG. 1;

FIG. 4 is a side elevational view, opposite the view of FIG. 3, of the polishing or grinding pad assembly with abrasive disk, spacer, reinforcement and pad of FIG. 1;

FIG. 5 is a rear elevational view of the polishing or grinding pad assembly with abrasive disk, spacer, reinforcement and pad of FIG. 1;

FIG. 6 is a front elevational view, opposite the view of FIG. 5, of the polishing or grinding pad assembly with abrasive disk, spacer, reinforcement and pad of FIG. 1;

FIG. 7 is an enlarged and exploded bottom perspective view of the polishing or grinding pad assembly with abrasive disk, spacer, reinforcement and pad of FIG. 1;

FIG. 8 is an enlarged rear elevational view of the polishing or grinding pad assembly with abrasive disk, spacer, reinforcement and pad of FIG. 1; and,

FIG. 9 is a top plan view of the polishing or grinding pad assembly with abrasive disk, spacer, reinforcement and pad of FIG. 1.

The even broken lines in the drawings illustrate portions of the polishing or grinding pad assembly with abrasive disk, spacer, reinforcement and pad that form no part of the claimed design.

1 Claim, 4 Drawing Sheets
